United States Patent Office

Des. 185,264
Patented May 26, 1959

185,264

ELECTRIC LAWN MOWER

Ross E. Cornwell, Chicago, Ill., assignor to Sunbeam Corporation, Chicago, Ill., a corporation of Illinois

Application November 12, 1958, Serial No. 53,345

Term of patent 14 years

(Cl. D40—1)

Fig. 1 is a front perspective view of an electric lawn mower embodying my new design; and

Fig. 2 is a rear perspective view thereof.

I claim:

The ornamental design for an electric lawn mower, as shown.
